1

This invention relates to a method of and apparatus for conditioning and/or cooling material consisting of large masses of individual particles such as aggregate and/or other ingredients of a concrete mix, prior to mixing.

It is common practice in large concrete construction projects to erect concrete mixing plants which include towers having bins adjacent the upper end thereof for receiving ingredients such as aggregates, sand and cement of the concrete mix. Below the bins are weighing devices which receive the ingredients from the bins, said weighing devices weighing and proportioning the particular ingredients and then delivering same to mixers arranged in the tower below the weighing devices and adapted for delivering mixed concrete to trucks for movement to a place of use. In such projects large quantities of aggregates and/or other ingredients must be available and said ingredients are commonly exposed to the climatic conditions so that the temperatures of same vary widely under normal operating conditions making it difficult to maintain uniform temperatures of the concrete mix.

It is desirable particularly in large concrete construction projects, such as large dams and the like to pour the concrete mix at a temperature which is above freezing and at the same time low enough that the heat generated by the setting process will not increase the concrete above 100° F. as at or about 125° F. concrete becomes like gelatin and will never set. The specifications on present dam contracts require the concrete mix to be controlled to a maximum of 65° F. and it is recognized it would be preferable to reduce the requirement to between 50° and 55° F. but until now such low pouring temperatures have not been obtainable under all climatic conditions. Current methods of cooling concrete mix with ice or inundation of the aggregate have been found objectionable. Only a limited quantity of ice can be used due to the small amount of water specified in the concrete mix and such a limited quantity of ice is incapable of producing the desired low temperature of the mix. Methods of cooling by inundation complicate the control of moisture, require special tanks for the aggregate in addition to the mixing tower bins, making the handling of the aggregate difficult and there is loss in cooling effect due to re-heating in the time lapse between cooling and mixing of the aggregate. Current methods using delivery of cold air from a central refrigeration and air cooling plant working on removal of sensible heat to the lower portion of a plurality

2

of aggregate bins in a mixing plant are objectionable due to necessary shut down time for defrosting or maintenance of the refrigeration plant and limitation of range of cooling due to the very large amount of air that must be forced through the aggregate because of small heat carrying capacity of air when operating on sensible heat change. Also such operations requiring a high rise of temperature of the air lower the required low temperature limit which causes frosting of the refrigerant coils.

The objects of the invention are to provide a method and apparatus for conditioning and/or cooling material which overcomes the noted disadvantages and objections of other methods; to provide a method of conditioning material in a plurality of bins whereby the material in and moving through the respective bins is conditioned and/or cooled independently of the other bins; to render the various operations involved with the conditioning and/or cooling of material as nearly continuous as possible; to provide apparatus for conditioning aggregate or the like by controlled movement of fluids through the aggregate while in a bin of a mixing tower; to provide conditioned air delivery mechanism and ducts so arranged to increase the initial surface of material exposed to the delivery of air and reduce the static head resisting movement of air through the aggregate; to provide a central refrigerating system located adjacent to the aggregate mixing plant and connected to the various aggregate bins by means of chilled water, brine, or fluid or refrigerant lines in such a manner that any portion of the central plant can be concentrated on any part or all of the bins that require cooling at a given time, the plant being proportioned in such a way that it has sufficient capacity without having to work at low enough temperatures to cause the coils to frost up and thereby lose capacity and require defrosting; to provide apparatus for cooling aggregate and the like in deep beds in bins by selectively delivering large volumes of cooling fluids to the upper levels of the bed and smaller volumes of cooling fluids at lower levels whereby most of the cooling is done in the upper portion of the bed with lower static head and power for movement of the fluid through the bed of material to progressively cool the aggregate and the like as it passes downwardly through the bin; to provide for applying water to the aggregate at the top of the bin, the quantity of the water being approximately that which will be evaporated by the heat in the aggregate in latent cooling resulting from

delivery of cooled dry air to the aggregate at lower points in the bin; to provide for cooling the aggregate and the like in a plurality of bins by delivering two fluids to the bins for counter-current flow through the aggregate and selectively controlling the flow of said fluids whereby they cooperate to effect evaporation cooling and removal of heat from the aggregate so the temperature and moisture content of the aggregate delivered from the bins are maintained; to provide for cooling of aggregate by selectively delivering liquid and air hereto and selectively recirculating all or a part of said air and liquid, said air and liquid being selectively cooled by a suitable refrigerating system whereby the temperature of the aggregate and water content thereof may be accurately controlled as desired; to provide individual air cooling and delivery and/or circulating mechanism for each bin to be cooled, the air being delivered in a plurality of stages to selected points in the bin for stage cooling of the aggregates and the like; and to provide a method and apparatus for cooling material such as aggregates and the like in bins of conventional concrete mixing towers, said apparatus being compact in construction and arranged to provide a continuous cooling of the material moving through the individual bins for maintaining selective individual delivery temperature and moisture content of the material, the material being cooled in stages whereby a maximum of cooling can be obtained efficiently with small power output, the cooling operation being flexible to meet varied conditions and specifications in the pouring of large masses of concrete.

In accomplishing these and other objects of the present invention, I have provided improved details of structure, the preferred forms of which are illustrated in the accompanying drawings, wherein:

Fig. 1 is an elevation of a concrete mixing tower having apparatus thereon for conditioning the material in the bins.

Fig. 2 is a vertical sectional view through concrete ingredient containing bins in the upper portion of the concrete mixing tower taken on the line 2—2, Fig. 3, said structure being arranged for multiple stage cooling and conditioning of said ingredients.

Fig. 3 is a plan view of a concrete mixing tower having aggregate cooling apparatus in accordance with the present invention, a refrigeration plant being shown diagrammatically in connection with the tower.

Fig. 4 is a partial vertical sectional view through a bin in a concrete mixing tower with a modified form of aggregate conditioning mechanism.

Fig. 5 is a partial sectional view through a bin of a concrete mixing tower, with a further modified form of conditioning mechanism.

Fig. 6 is a sectional view on the line 6—6, Fig. 5, illustrating a grizzly in the bin for the drainage of liquid from the concrete ingredients in said bin.

Referring more in detail to the drawings:

1 designates a concrete mixing plant which consists of a tower 2 constructed of structural steel or the like and arranged to support a plurality of hoppers or bins in the upper portion thereof. It is preferable that the bins be so arranged that a central bin 3 serves as a reservoir for cement 4 and other bins 5 arranged around the bin 3 serving to contain gravel, crushed stone

or other aggregate 6 and sand 7, the number of bins holding the respective materials being approximately in proportion to the relative quantity of the respective materials used in the concrete mix. The bins are so constructed as to provide a deep bed of material or ingredients of the concrete mix contained therein. The cement bin 3 has downwardly converging bottoms 8 terminating in spouts 9 having gates 10 thereon to control the flow of cement from the bin 3. Each of the bins 5 has inwardly sloping bottoms 11 terminating in spouts 12 having gates 13 for control of the flow of the cement ingredient contained in the respective bins. Arranged in the tower below the bins in a position to receive the concrete ingredients from the bin spouts are weighing devices 14 for measuring and proportioning the concrete ingredients and selectively delivering same to concrete mixers 15 arranged in the tower below the weighing devices. The weighing devices 14 and mixers 15 may be of any conventional construction and are preferably arranged in the tower for gravity flow of the ingredients from the bins to the weighing devices and then to the mixers, and from the mixers to suitable means, such as trucks, for conveying the concrete to a place of use, such as a dam site.

In the bin structure illustrated, the cement bin 3 is formed by side walls 16 extending upwardly from the bottom 8, said side walls preferably being arranged in a polygonal shape and forming inner walls of the bins 5. Outer side walls 17 extend upwardly from the bottoms 11 in spaced relation to the walls 16 and partitions 18 divide the space between the walls 16 and 17 into a plurality of bins 5. A cover 19 preferably converges upwardly from the upper ends of the side walls 17 and has engagement with the walls 16 to enclose the respective bins. Rotatively mounted at the apex of the cover 19 is a hopper 20 for receiving the various concrete ingredients, said hopper being provided with a spout 21 so arranged that the hopper may be rotated to position the spout 21 for selective discharge through chutes 22 to the respective bins 5 or may be positioned between the chutes for the discharge of cement into the bin 3. With this arrangement the various ingredients of the concrete mix may be delivered to the hopper 20 of the tower 1 and selectively discharge into the bins at intervals to maintain the levels of the ingredients in the respective bins between selected maximum and minimum heights.

Cooling apparatus 23 is provided for each of the bins containing aggregate, sand or the like. The cooling apparatus 23 for each bin includes a coil 24 preferably arranged horizontally and fixed in a housing 25 having side and top walls 26 and 27 and an opening 28 in the bottom, the housing and coil being supported by suitable members 29 on the tower structure and preferably arranged adjacent a decking 30 extending around the tower for movement of persons inspecting and maintaining the equipment. Each of the coils is preferably connected with cooling fluid supply and return manifolds 31 and 32 respectively for chilling said coils, suitable valves 33 being arranged for individual control of the fluid delivered to the respective coils. The manifolds 31 and 32 are connected by suitable pipes 34 and 35 respectively to suitable refrigeration apparatus in a refrigeration plant 36.

The plant 36 includes a plurality of refrigerant compressors 37, a condenser 38 and evaporator coils 39 in a heat exchanger 39, whereby water

may be circulated by a pump 40 through the heat exchanger in contact with the evaporator coils and the chilled water pumped through the manifold 31 for supplying the respective coils with chilled water. In normal operations it is preferred to use chilled fluid in the coils 24 in order to eliminate any frosting condition. However, if desired, the refrigerant compressed by the compressors 37 may be delivered direct to the manifolds 31 for supplying the coils 24 so said coils will serve as the evaporator coils of the refrigeration system. If refrigerant is circulated through the coils 24, suitable controls will be used to maintain the coil operation above the temperature at which frosting occurs.

The material in each of the bins is cooled substantially in the same manner, with individual controls in the cooling equipment for regulating the cooling and/or conditioning of the material in the respective bins, whereby the equipment will properly function to cool aggregate, sand and the like having different particle sizes and different static head for air circulation through the material in the bins. A fan 41 capable of delivering a relatively large volume of air at low static head is suitably mounted on the tower and has its intake communicating by means of a duct 42 with the interior of the respective coil housing 25 whereby the fan draws air through the opening 28 in the housing over the coils and through the duct 42. The air is discharged by the fan 41 through a duct 43 extending into the respective bin 5 and terminating in a downwardly directed frustro-conical outlet 44 located below the minimum level of material in the bin. The outlet 44, being directed downwardly in the material, acts as an outlet of a Venturi tube and serves to convert the velocity energy of the air into static head as required for maintaining movement of air through the material to be cooled. Also the material whether fine or coarse will move outwardly and downwardly along the wall 45 of the outlet member and then slip downwardly past the edge of the wall and inwardly whereby the material itself forms an inverted cone-shaped space 46 below the outlet 44, thereby providing a considerably greater area of material surface exposed to the air delivered by the duct 43. This large area of initial surface of the material exposed to the air from the duct 43 reduces the initial static loss of starting flow of air through the material. The walls 45 of the outlet 44 may be perforated to form openings 47 which are smaller than the size of the aggregate being handled in the respective bin so that no material will pass through said openings but air may pass through the openings into material thereby further increasing the surface of the material exposed to the cool air delivered by the fan 41. As illustrated in Fig. 2 the outlet member 44 is located relative to the sides of the bin 5 and the normal slope of the upper surface of the material in the bin to substantially equalize the movement of the air from the outlet member through the material completely around the outlet member and thereby avoid any stratification or channeling through the material.

A second fan 48 preferably operating at higher static head and lower volume than the fan 41 is suitably supported in the tower adjacent the coil housing 25 and has its inlet connected by a duct 49 with said housing to also draw air over the coils 24, said fan 48 discharging the air through a duct 50 extending into the bin 5 and 70 75

terminating in a downwardly turned frustro-conical outlet member 51 centrally located in the material in the bin adjacent the spout 12. The material moves downwardly over the wall of the outlet member 51 and also converges inwardly to form an inverted cone-shaped space 52 below the outlet member, the wall 53 of said outlet member preferably having openings 54 therein for discharge of air into the material in the same manner as the air is discharged from the outlet member 44. Dampers 55 and 56 are located in the ducts 42 and 49 respectively for aid in controlling relative movement of air by the fans 41 and 48, and also permitting either of the fans to operate singularly for discharging air into the material in the bin 5 for cooling same, particularly where the reduction in temperature required is relatively small.

Stacks 57 are arranged on the cover 19 above each of the bins 5 for escape of air and moisture from the bin to the atmosphere, said stacks preferably having dampers 58 for selective control of the area of the opening in the stack for the passage of air therethrough. Any suitable means may be applied to the ends of the stacks for preventing rain and the like from entering the bins through said stack.

A plurality of spray pipes 59 are arranged in each bin 5 adjacent the cover 19 for substantially uniformly spraying water over the upper surface of the material contained in the bin. The spray pipes 59 preferably have communication with a manifold 60 which is connected by a pipe 61 with the manifold 62 suitably arranged on the tower and having connection with the spray pipes in the various bins 5, a valve 63 preferably being arranged in each of the pipes 61 for individual control of the quantity of water sprayed in the respective bin. The manifold 62 is supplied with water under pressure by a pipe 64 leading to a suitable source of water supply and said water may be chilled in the refrigeration plant if desired. It is preferable that the quantity of water sprayed on the material in the bins be such that the air delivered to the material in the bins by the fans 41 and 48 will evaporate substantially all of the water from the material whereby said material is substantially dry when discharged from the spouts 12, the evaporation of said water cooling the material. An automatic control for the valve 63 may be arranged by providing a differential wet and dry bulb instrument 65 arranged in or adjacent each of the stacks of the bins 5 and connected with the valves 63 to cut off the supply of water sprayed on the material when the differential approaches a selected minimum and to open the valves to provide additional spray when the differential approaches a maximum. If the material is too dry the sensible heat will increase the differential and turn on more water.

The operation of the apparatus illustrated in Figs. 2 and 3 in practicing the method for cooling of material is such that the quantities of water and air delivered to the bins and the relative proportions of same may be regulated to provide efficient cooling of the material and regulation of moisture content to a desired amount regardless of outside atmospheric conditions. The material is delivered to the hopper 20 and directed by the spout 21 through a selected chute 22 into a bin 5 until the bin is filled above a minimum height which must be above the outlet member 44. The refrigerating plant 36 is operated to provide desired coolant in the coils 24 which are

preferably operated in such a manner that the temperature thereof is just above the frost point. To assure such operation the compressors preferably move refrigerant through the heat exchanger 39 for chilling water, brine or the like liquid to a temperature slightly above the freezing point of the liquid. The liquid is pumped through the manifold 31 and selectively admitted to the respective coils 24 by adjustment of valves 33. Water which may be chilled if desired is delivered through the pipe 64 to the manifold 62 and supplied onto the surface of the material in the bins 5, wetting said material and also additional material which is delivered to the bins to maintain the level above a minimum therein and replace the material removed through the spout 12. The fans 41 and 48 are operated to draw air through the openings 28 around the coils 24 chilling and also condensing moisture from the air whereby relatively dry cold air is moved by the fans 41 and 48 and delivered to the material through the outlet members 44 and 51. The air delivered by the fan 41, being of relatively high volume and low static head, tends to evaporate the water on or in said material to cool same by evaporation and the latent heat is carried away in the air. The large quantity of air delivered by fan 41 removes most of the moisture whereby the air delivered by the fan 48 is capable of substantially drying or evaporating the moisture in the material passing thereby to the spout 12 and further cools the material to reduce the temperature thereof to approximately 45° F.

If the material delivered to the bin 5 is relatively wet as when there has been rain on a storage pile exposed to the atmosphere, less water will be delivered by the spray pipes 59. When less reduction in the temperature of the material is required, as when the atmosphere is cool, it is possible to provide the cooling by air from only one fan or the proportions of air delivered by the fans 41 and 48 may be adjusted by the dampers 55 and 56 for most efficient cooling. In extreme cold temperatures heated liquid may be passed through the coils 24 for heating the air delivered to the material and thereby maintain the temperature substantially as desired. Obviously the entire equipment is such that each portion and each bin may be adjusted and regulated to meet substantially any requirements imposed by climatic conditions and still maintain the temperature of the materials delivered through the spouts 12 whereby the final mix will be according to the specifications required on the construction project. The cooling of the material is effected continuously while the material is fed to and drawn from the bins and in effect the cooling is on the principle of counterflow as the material and water move downwardly through the bins the air moves upwardly through the material, the cooled air becoming warmer and increases in moisture content as it moves upwardly through warmer and wetter material and the air total heat content exceeds that normally exhausting in outdoor air and air is exhausted from the system, all of the apparatus being arranged to accomplish a maximum in efficiency in cooling of the material with a minimum of power. To further illustrate the operating conditions of the apparatus the following is an example of the operating characteristics, temperatures and air flow at selected material and climatic temperatures in the operation of a concrete plant having a capacity of 175 cubic yards per hour. Assuming that the aggregate is delivered to the six

material bins 5 illustrated at a temperature of 100° F. and said aggregate cooled and delivered through the spouts 12 at a temperature of 45° F. there would be required approximately 672 tons of refrigeration, or in other words the cooling of the material in the bin would be at an average rate of 112 tons of refrigeration to each bin per hour to remove 8,064,000 B. t. u. per hour. Water or other suitable liquid is chilled in the refrigeration plant and circulated through the coils 24 at a supply temperature of approximately 34° F. Assuming the outside air drawn over the coils by the fans 41 and 48 is 100° F. dry bulb, 72° F. wet bulb, and 35.8 total heat and the chilled liquid circulated through the coils 24 sufficiently to reduce the air to a temperature of 40° F. dry bulb, 39° F. wet bulb and 14.6 total heat, 12.7 cubic feet per pound of air, the air will move upwardly through the aggregate, cooling and evaporating the liquid on same. To cool the aggregate by combined latent and sensible heat methods, the fans are operated to move sufficient air through the aggregate whereby the air exhausted through the stack at the top of the bins has a temperature of 92° F. dry bulb, 90° F. wet bulb and 55.18 total heat per pound, that is, the total heat content of the air is increased 41.2 B. t. u. per pound which heat is absorbed from the aggregate. The air moved through the aggregate under these conditions is determined as follows:

$$\begin{aligned} C. F. M. &= \frac{112 \text{ T. R.} \times 200 \text{ B. t. u./ton}}{41.2 \text{ T. H. absorbed/lb.} + 12.7 \text{ cu. ft./lb.}} = \\ &= 6900 \text{ cu. ft./min.} \end{aligned}$$

If all of the heat of the aggregate were removed by evaporation in the form of vapor the water evaporated would equal

$$\frac{8,064,000}{970} = 8,320 \text{ pounds per hour of water}$$

The per cent of heat removed by a sensible heat is approximately 25 per cent. Therefore, $8,320 \times 25\%$ equals 2,080 pounds of water. 8,320 less 2,080 equals 6,240 pounds of water, which is added for evaporative cooling. Batch water usually required for concrete mix amounts to 100 pounds per cubic yard and for 175 cubic yards per hour would require 17,500 pounds of water per hour, so the amount of water added for evaporative cooling even if only partly removed would not leave the aggregate too wet.

It is customary in concrete mixing towers for the depth of the material in the bins to be more than 17 feet. In the present structure it is contemplated that the average depth of the material from the lower air outlet be approximately 17 feet and that the air from the upper outlet be forced upwardly only through approximately 4 feet of material whereby less static head is required and also less horsepower to drive the fans than would be necessary if all of the air were forced through the total height of the bins. For moving 6,900 cubic feet of air per minute in each of the bins, that is a total of 41,400 cubic feet per minute through the entire six bins of aggregate requires approximately 120 horsepower. The tons of refrigeration used equal

$$\frac{35.8 - 14.6 \times 6900}{12.7 \times 200} = 57.5$$

tons of refrigeration. The required refrigeration is reduced from 112 tons to 57.5 tons since fresh air used under design conditions contains 35.8 B. t. u. per pound total heat and spent air as

exhausted containing 55.18 B. t. u. 57.5 T. R. for each of six bins equals 345 horsepower refrigeration load plus 120 horsepower fan load equals total of 465 horsepower for the entire cooling of 175 cubic yards per hour from 100° F. to 45° F.

In the form of the invention illustrated in Fig. 4, chilled water or refrigerant is delivered to a manifold 66 having branches 67 connected with coils 68, suitably mounted in housings 69, each of which has communication with the upper end of a bin 5 through the cover 19. The return from the coil 68 is connected to a manifold 70 for the return of liquid to the refrigeration plant. A fan 71 is arranged adjacent to the housing 69 and has communication with the interior thereof above the coil 68 whereby air is drawn from the housing and forced by the fan 71 through a duct 72 which extends into the respective bin 5 and terminates in a downwardly turned outlet member 73 constructed substantially the same as the outlet members 44, suitable dampers 74 being provided in the duct 72 for controlling the opening therein. A fan 75 capable of moving air at high static head has its inlet connected by a duct 76 with the housing 69 for communication therewith above the coil 68 whereby air is drawn from the housing to the fan and delivered through a duct 77 which extends into the bin 5 and terminates in a downwardly directed outlet member 78 constructed and located substantially the same as the outlet member 51 in the form of the invention illustrated in Fig. 2, a damper 79 being arranged in the duct 76 for control of the flow of air therethrough. Communicating with the housing 69 is a stack 80 opening to the atmosphere, said stack having a damper 81 for control of the opening through the stack and thereby controlling make-up air delivered to the housing 69. Also a damper 81' is arranged in the housing 69 for controlling flow of air over the coils 68 whereby all or any part of the air moved by the fan 75 may be drawn through the stack 80 from outside if desired.

In this form of the invention water, chilled if desired, is supplied to a manifold 62 for delivery through the valve controlled lines 61 to the spray pipes 59 located in the bin adjacent the cover 19. Also connected to the manifold 62 is a pipe 82 having a valve 83 therein controlling flow of water through the line, said pipe 82 being connected with spray pipes 84 located in the housing 69 above the coil 68. With this arrangement of the structure the material is delivered to the tower and through the chute 22 to the bin 5 to replace material drawn from the bin through the spout 12 and maintain the level of the material between a minimum and a maximum height in the bin. Chilled water or cooling media is supplied to the coil 68 and the fans 71 and 75 operated to draw air from the bin 5 over the coil 68 from the housing 69 and deliver same to the bin by way of the outlet members 73 and 78, which air moves upwardly through the material cooling same and to the upper portion of the bin where said air is again drawn over the coil 68 thereby providing recirculation of the air used for cooling the material. Damper 81 is adjusted to selectively add make-up air to the recirculated air to replace air lost in the apparatus and also to replace air that is allowed to escape through a stack 85 having a damper 86 therein. The control of the dampers 81 and 86 regulates the amount of air that is recirculated in proportion to make-up

air drawn from the atmosphere and aid in controlling the moisture content of said air.

Water is sprayed from the spray pipes 84 over the coils 68 removing dirt and any frost therefrom, thereby keeping said coil clean for greatest heat transfer. The water sprayed on the coil may be dropped onto eliminators or the like for removal or dropped onto the material in the bin if desired. Also water is sprayed from the spray pipes 59 for wetting of the material in the bin 5, said water being regulated to substantially the quantity which the air applied by the fans 71 and 75 will evaporate in the cooling of the material to maintain substantially dry material at the spout 12. The delivery of air by the fans 71 and 75 may be individually regulated. The temperature of the cooling media in the coils 68 for the respective bin, the dampers 81 and 86, and water supplied by the sprays 59 and 84 are regulated to provide the desired temperature content of the material delivered from the bin. The use of a separate unit for each bin permits the portions of said units to be adjusted to accommodate the cooling of materials of various sizes, thereby efficiently cooling the material whether it be sand, aggregate or relatively coarse stone.

In the form of the invention illustrated in Figs. 5 and 6, the bins 5 have a spout 12, inner wall 16, outer wall 17 and cover 19, of substantially the same construction as illustrated in Fig. 2. The bottom of the bin is provided with a grizzly 87 formed of a plurality of members, such as railroad rails, arranged with said members close together whereby the material in the bin 5 will slide over the top of the grizzly toward the spout 12 while water or other liquid drains between the grizzly members. The bin is provided with a sump 88 located below the grizzly and preferably so constructed for access to the sump for cleaning dust, dirt and the like therefrom. Communicating with the sump is a drain pipe 89 which leads to a reservoir 90 through which the liquid flows over a plurality of baffles to further settle out any dirt and the like therefrom, the reservoir being provided with manholes or the like providing access for cleaning of the reservoir. Connected with the reservoir is a valve-controlled pipe 91 for selectively adding make-up liquid to the system to replace any liquid lost therein. Liquid is drawn from the reservoir through a suitable heat exchanger 92 where said liquid comes in contact with coils or the like of a refrigeration system for cooling the liquid. The chilled liquid is then pumped by means of a pump 93 through a pipe 94 leading to spray pipes 95 that are located in the bin adjacent the cover 19. Suitable valves 96 are provided in the line 94 for controlling the spray and quantity of water delivered to the bin 5. Material is supplied through the chute 22 to the bin 5 and the chilled water sprayed thereon for flow downward through the material in the bin. A baffle or deflector 97 diverts all of the material and liquid over the grizzly 87 whereby substantially all of the water is drained from the material. This water circulation system is of the balanced head type to reduce the power required for circulating the water in the system and the chilled water flowing over the material and through same absorbs the heat therefrom so the material moving over the grizzly is wet and is cooled, for example to approximately 60° F. A portion of the chilled water from the pump 93 is selectively directed through a coil 98, the re-

turn of which is connected with the pipe 89. Air is drawn over the coil 98 by a fan 99 and discharged through a duct 100 which extends into the bin 5 between the grizzly and the spout 12, said duct 100 terminating in a downwardly directed frusto-conical outlet member 101, the coils 98 removing moisture from the air passing therearound causing the air discharged through the outlet member 101 to be relatively dry and chilled, whereby the air moves through the material in the bin providing evaporation for additional cooling of same. The location of the outlet member causes the air to dry the material before it reaches the spout 12 and the air moves upwardly through the material and out to the atmosphere through a stack 102 which has a damper 103 for controlling the opening therein. The cooling and the evaporation effected by the air delivered to the material adjacent the spout will further reduce the temperature of said material to suitable temperatures, for example 40° to 45°.

While the apparatus specifically described is for using my invention in the cooling of aggregate, it may be also used for the cooling and drying of other materials. For example, foods such as peas and the like may be precooled, dried and then frozen by the application of fluids in stages wherein the temperature and moisture content of the fluids are regulated.

It is believed obvious that I have provided a method and apparatus for cooling of material as it moves through the individual bins and also controlling the moisture content in an efficient and economical manner, that is flexible to meet varied conditions and specifications as to temperatures of the materials.

What I claim and desire to secure by Letters Patent is:

1. The method of conditioning a large volume of material consisting of individual particles moving downwardly through a confined area by altering the temperature thereof, including applying chilled water to the material to thoroughly permeate same and intermingle in direct contact with the individual particles, draining excess water from the material, and delivering air to the wet material for movement therethrough countercurrent to the application of the water, said air being in sufficient volume to substantially evaporate the water remaining in the material and cool the particles in the volume of material whereby the temperature and moisture content of the material leaving the confined area are substantially uniform.

2. The method of conditioning a large volume of aggregates consisting of individual particles slowly moving downwardly in a confined area by altering the temperature thereof for incorporation with other ingredients in a concrete mix, including applying water to the aggregate as it enters the confined area cooling and drying air, delivering the cooled dry air to the wet aggregate for movement therethrough countercurrent to the movement of the aggregate through the confined area, said air being in sufficient volume to substantially evaporate the water applied to the aggregate and cool the particles in the volume of aggregate, and controlling the quantity of water applied to the aggregate in accordance with the relative moisture content of the air leaving the confined space whereby the temperature and moisture content of the aggregate leaving the confined area are substantially uniform.

3. The method of continuously conditioning a large volume of material consisting of individual particles as it gravitates through a confined area, including wetting the material as it enters the confined area, cooling and drying air, selectively delivering the cooled dried air to the material at spaced points in the confined area for movement through the material, said air being in greater volume than necessary to substantially evaporate the water from the wetted material for latent cooling of the material, and controlling the wetting of the material as it enters the confined area in accordance to the relative moisture content of the air being released from the confined area whereby the temperature and moisture content of the material leaving the confined area are substantially uniform.

4. The method of continuously conditioning a large volume of material consisting of individual particles as it gravitates through a confined area, including wetting the material as it enters the confined area, cooling and drying air, selectively delivering the cooled dried air to the material as spaced points in the confined area for movement through the material, said air being released from the confined area adjacent the entrance for the material, said air being in greater volume than necessary to substantially evaporate the water from the wetted material for latent cooling of the material, the excess air effecting additional sensible cooling of the material, and controlling the wetting of the aggregate as it enters the confined area in accordance to the relative dry and wet bulb temperatures of the air being released from the confined area whereby the temperature and moisture content of the material leaving the confined area are substantially uniform.

5. The method of continuously conditioning a large volume of aggregate as it gravitates through a confined area for incorporation with other ingredients in a concrete mix, including wetting the aggregate as it enters the confined area, cooling and drying air, selectively delivering the cooled dried air to the aggregate at spaced points in the confined area for movement through the aggregate in countercurrent relation to the movement of the aggregate through the confined area, said air being released from the confined area adjacent the entrance for the aggregate, said air being in greater volume than necessary to substantially evaporate the water from the wetted aggregate for latent cooling of the aggregate, the excess air effecting additional sensible cooling of the aggregate, and controlling the wetting of the aggregate as it enters the confined area in accordance to the relative dry and wet bulb temperatures of the air being released from the confined area whereby the temperature and moisture content of the aggregate leaving the confined area are substantially uniform.

6. Apparatus for conditioning granular material comprising, a bin adapted to contain a quantity of granular material and arranged for gravitation of said material therethrough, said bin having a controlled outlet for the material adjacent the lower portion of said bin, an air cooling device, means for supplying cooling medium to the air cooling device, means for moving air through the air cooling device and selectively delivering said air into the material at spaced levels therein for flow upwardly through said materials, and means for controlling the quantity of air and the temperature of same de-

livered to the material to cool said material whereby the material passing through the outlet of the bin is substantially uniform in temperature.

7. Apparatus for conditioning granular material comprising, a bin adapted to contain a quantity of granular material and arranged for gravitation of said material therethrough, said bin having a controlled outlet for the material adjacent the lower portion of said bin, means for directing material to the bin, said material being maintained above a predetermined minimum level in the bin, means for wetting the material in the upper portion of the bin, an air cooling device supported adjacent the bin, means for supplying a cooling medium to the air cooling device, and means for moving air through the air cooling device and selectively delivering it in the material at spaced levels therein for flow upwardly through said material, the cooled air being of sufficient volume to substantially dry the wetted material for latent cooling of same whereby the material passing through the outlet of the bin is substantially uniform in temperature and moisture content.

8. Apparatus for conditioning granular material comprising, a bin adapted to contain a quantity of granular material and arranged for gravitation of said material therethrough, said bin having a controlled outlet for the material adjacent the lower portion of said bin, means for directing material to the bin, said material being maintained above a predetermined minimum level in the bin, means for applying liquid to the material in the upper portion of the bin, means for controlling the quantity of liquid applied to the material in accordance to the wet and dry bulb temperature at the upper portion of the bin, an air cooling device supported adjacent the bin, means for supplying a cooling medium to the air cooling device, and means for moving air through the air cooling device and selectively delivering it in the material at spaced levels therein for flow upwardly through said material, the cooled air being of sufficient volume to substantially evaporate the liquid in the material for latent cooling of same and further sensibly cool said material whereby the material passing through the outlet of the bin is substantially uniform in temperature and moisture content.

9. Apparatus for conditioning granular material comprising, a bin adapted to contain a quantity of granular material and arranged for gravitation of said material therethrough, said bin having a controlled outlet for the material adjacent the lower portion of said bin, means for directing material to the bin, said material being maintained above a predetermined minimum level in the bin, means for spraying liquid into the upper portion of the bin onto the material therein, means for controlling the quantity of liquid sprayed into the bin in accordance to the wet and dry bulb temperature at the upper portion of the bin, an air cooling device supported adjacent the bin, means for supplying a cooling medium to the air cooling device, means for moving air through the air cooling device and selectively delivering it in the material at spaced levels therein for flow upwardly through said material, and means for controlling the volume and temperature of air delivered to the material to substantially evaporate the liquid in the material for latent cooling of same and further sensibly cool said material where-

by the material passing through the outlet of the bin is substantially uniform in temperature and moisture content.

10. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material therethrough, each of said bins having a controlled outlet adjacent the lower portion thereof, means for selectively directing aggregates, sand and the like to the respective bins whereby the material contained in the respective bins is maintained above a predetermined minimum level, an air cooling device supported adjacent each of the respective bins, means for supplying cooling medium to the air cooling devices, means for individually controlling the cooling medium supplied to the respective cooling devices for regulating the temperature thereof, a plurality of air ducts connected with the air cooling devices of the respective bins and terminating in vertically spaced outlets in said bins, and means for moving air through the air cooling devices and delivering the air through the ducts to the respective bins for flow upwardly through the material therein whereby the material is cooled and maintained substantially uniform in temperature until it passes through the outlet of the respective bins.

11. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material therethrough, each of said bins having a controlled outlet adjacent the lower portion thereof, means for selectively directing aggregates, sand and the like to the respective bins whereby the material contained in the respective bins is maintained above a predetermined minimum level, means in each of the bins for delivering liquid into the upper portion thereof onto the material therein, means for individually controlling the quantity of liquid delivered into the respective bins in accordance to the wet and dry bulb temperature at the upper portions of the respective bins, a plurality of air ducts extending into the respective bins and terminating in vertically spaced outlets in said bins, and means for moving air through the ducts to the respective bins for flow upwardly through the material therein, the air being of greater volume than that required for substantially evaporating the water in the material for latent cooling of same whereby the material is cooled and maintained substantially uniform in temperature and moisture content until it passes through the outlet of the respective bins.

12. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material therethrough, each of said bins having a controlled outlet adjacent the lower portion thereof, means for selectively directing aggregates, sand and the like to the respective bins whereby the material contained in the respective bins is main-

tained above a predetermined minimum level, means in each of the bins for spraying liquid into the upper portion thereof onto the material therein, means for individually controlling the quantity of liquid sprayed into the respective bins in accordance to the wet and dry bulb temperature at the upper portions of the respective bins, an air cooling device supported adjacent each of the respective bins, means for supplying cooling medium to the air cooling devices, means for individually controlling the cooling medium supplied to the respective cooling devices for regulating the temperature thereof, a plurality of air ducts connected with the air cooling devices of the respective bins and terminating in vertically spaced outlets in said bins, and means for moving air through the air cooling devices and delivering the air through the ducts to the respective bins for flow upwardly through the material therein, the cooled air being of greater volume than that required for substantially evaporating the water in the material for latent cooling of same whereby the material is further sensibly cooled and maintained substantially uniform in temperature and moisture content until it passes through the outlet of the respective bins.

13. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material therethrough, each of said bins having a controlled outlet adjacent the lower portion thereof, means for selectively directing aggregates, sand and the like to the respective bins whereby the material contained in the respective bins is maintained above a predetermined minimum level, means in each of the bins for spraying liquid into the upper portion thereof onto the material therein, means for individually controlling the quantity of liquid sprayed into the respective bins in accordance to the wet and dry bulb temperature at the upper portions of the respective bins, an air cooling device supported adjacent each of the respective bins, means for supplying cooling medium to the air cooling devices, means for individually controlling the cooling medium supplied to the respective cooling devices for regulating the temperature thereof, a plurality of air ducts connected with the air cooling devices of the respective bins and terminating in vertically spaced outlets in said bins, means for moving air through the air cooling devices and delivering the air through the ducts to the respective bins for flow upwardly through the material therein, the cooled air being of greater volume than that required for substantially evaporating the water in the material for cooling of same and carrying latent heat from the material in the air whereby the material is further sensibly cooled and maintained substantially uniform in temperature and moisture content until it passes through the outlet of the respective bins, stacks communicating with the upper portions of the respective bins, and means in said stacks for controlling the escape of air therethrough.

14. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material

therethrough, each of said bins having a controlled outlet adjacent the lower portion thereof, means for selectively directing aggregates, sand and the like to the respective bins whereby the material contained in the respective bins is maintained above a predetermined minimum level, an air cooling device supported adjacent each of the respective bins, means for supplying cooling medium to the air cooling devices, means for individually controlling the cooling medium supplied to the respective cooling devices for regulating the temperature thereof, a plurality of air ducts connected with the air cooling devices of the respective bins and terminating in vertically spaced outlets in said bins, means for moving air through the air cooling devices and delivering the air through the ducts to the respective bins for flow upwardly through the material therein whereby the material is cooled and maintained substantially uniform in temperature until it passes through the outlet of the respective bins, stacks communicating with the upper portions of the respective bins, means in said stacks for controlling the escape of air therethrough, means on the air inlet of the air cooling device connected with the upper portion of the bin for providing the communication therewith whereby air is drawn from the respective bins through the air cooling device for recirculation through the bins, and means for controlling the proportions of the make-up air and recirculated air passing through the air cooling devices.

15. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material therethrough, each of said bins having a controlled outlet adjacent the lower portion thereof, means for selectively directing aggregates, sand and the like to the respective bins whereby the material contained in the respective bins is maintained above a predetermined minimum level, means in each of the bins for spraying liquid into the upper portion thereof onto the material therein, means for individually controlling the quantity of liquid sprayed into the respective bins in accordance to the wet and dry bulb temperature at the upper portions of the respective bins, an air cooling device supported adjacent each of the respective bins, means for supplying cooling medium to the air cooling devices, means for individually controlling the cooling medium supplied to the respective cooling devices for regulating the temperature thereof, a plurality of air ducts connected with the air cooling devices of the respective bins and terminating in vertically spaced outlets in said bins, means for moving air through the air cooling devices and delivering the air through the ducts to the respective bins for flow upwardly through the material therein, the cooled air being of greater volume than that required for substantially evaporating the water in the material for latent cooling of same whereby the material is further sensibly cooled and maintained substantially uniform in temperature and moisture content until it passes through the outlet of the respective bins, stacks communicating with the upper portions of the respective bins, and means in said stacks for controlling the escape of air therethrough.

16. Apparatus for continuously preconditioning aggregates, sand and the like consisting of individual particles for incorporation with other ingredients in a concrete mix comprising, a plurality of adjacent bins adapted to selectively contain quantities of aggregates, sand and the like and arranged for gravitation of said material therethrough, each of said bins having a controlled outlet adjacent the lower portion thereof, means for selectively directing aggregates, sand and the like to the respective bins whereby the material contained in the respective bins is maintained above a predetermined minimum level, means in each of the bins for spraying liquid into the upper portion thereof onto the material therein, means for individually controlling the quantity of liquid sprayed into the respective bins in accordance to the wet and dry bulb temperature at the upper portions of the respective bins, an air cooling device supported adjacent each of the respective bins, means for supplying cooling medium to the air cooling devices, means for individually controlling the cooling medium supplied to the respective cooling devices for regulating the temperature thereof, a plurality of air ducts connected with the air cooling devices of the respective bins and terminating in vertically spaced outlets in said bins, means for moving air through the air cooling devices and delivering the air through the ducts to the respective bins for flow upwardly through the material therein, the cooled air being of greater volume than that required for substantially evaporating the water in the material for latent cooling of same whereby the material is further sensibly cooled and maintained substantially uniform in temperature and moisture content until it passes through the outlet of the respective bins, stacks communicating with the upper portions of the respective bins, means in said stacks for controlling the escape of air therethrough, means on the air inlet of the air cooling device connected

with the upper portion of the bin for providing the communication therewith whereby air is drawn from the respective bins through the air cooling device for recirculation through the bins, and means for controlling the proportions of the make-up air and recirculated air passing through the air cooling devices.

16. Apparatus for conditioning a large mass of aggregates consisting of individual particles for incorporation with other ingredients in a concrete mix comprising, a bin adapted to contain a quantity of the aggregates and arranged for gravitation of said aggregates therethrough, said bin having a controlled outlet for the aggregates adjacent the lower portion thereof, means for directing aggregates into the upper portion of the bin, said aggregates being maintained above a predetermined minimum level in the bin, means for spraying chilled liquid into the upper portion of the bin onto the material therein, means for controlling the quantity and temperature of the liquid sprayed into the bin, means in the path of gravitation of the aggregate through the bin toward the outlet thereof for draining excess liquid from the aggregate,
